UNITED STATES PATENT OFFICE.

GEORGE E. HULSE, OF NEW HAVEN, CONNECTICUT, ASSIGNOR TO THE SAFETY CAR HEATING & LIGHTING COMPANY, A CORPORATION OF NEW JERSEY.

GENERATOR MOUNTING FOR RAILWAY CARS.

Application filed February 27, 1924. Serial No. 635,401.

To all whom it may concern:

Be it known that I, GEORGE E. HULSE, a citizen of the United States, and a resident of the city of New Haven, in the county of New Haven and State of Connecticut, have invented an Improvement in Generator Mountings for Railway Cars, of which the following is a specification.

This invention relates to generator mountings for railway cars.

One of the objects of the invention is to provide apparatus of the above nature practical and efficient and capable of meeting the requirements of practical use in a highly satisfactory manner. Another object is to provide such apparatus strong and durable and capable of dependable long continued service with infrequent attention. Another object is to provide apparatus of the above nature wherein the parts are compactly disposed and readily accessible in case the need of repair or replacement should arise. Another object is to provide such apparatus wherein the moving parts are efficiently and dependably lubricated. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of various possible embodiments of this invention,

Figure 1 is a top plan view of the apparatus.

Figure 2 is a side view looking transversely of the car.

Figure 3 is a section taken substantially along the line 3—3 of Figure 1 and viewed in the direction indicated by the arrows, and,

Figure 4 is a detached vertical section of certain parts shown in the preceding figures.

Similar reference characters refer to similar parts throughout the several views of the drawings.

Referring now to the drawings in detail, there is shown a generator 10 suspended beneath a railway car and adapted to be driven through its pulley 11 by a belt from an axle of the car. These latter parts are

not shown in the drawing in order to avoid needlessly encumbering the same. It will be understood, however, that the driving belt extends from the pulley 11 in the direction indicated by the arrow 12, in Figure 1 to an axle of the car. In Figure 3 are shown the center sill and a side sill of the car frame which run longitudinally of the car. The center sill in this instance comprises two parallel members 13 and 14 of the usual I-beam construction and a side sill is diagrammatically represented at 15, Fig. 3. Extending between the center sill member 13 and the side sill 15 are a pair of parallel lateral cross-members 16 and 17 which may be secured to the members 13 and 15 as by rivets 18. These cross-members 16 and 17 are preferably straps or bars of forged steel and may be shaped as required to suit the needs of the particular car upon which the apparatus is mounted.

Resting upon the upper surfaces of the supporting members 16 and 17 is a plate member 19 which bridges the space between the two supporting members and is preferably cut away at its central portion, as clearly shown in Figure 1. The side portions 19^a and 19^b of the plate 19 are preferably curved downwardly as brought out in Figure 2, and provided with re-enforcing ribs 20 so that the parts 19^a and 19^b are shaped in the nature of pillow-blocks which support bearings 21 for a shaft 22. These bearings 21 and their associated parts will be later described.

About the shaft 22, between the two bearings 21, is a lug 23 from which extend two downward arms 24 and 25 joined to the casing of the generator 10. The shaft 22 thus carries the weight of the generator through this lug 23 and the connecting arms 24 and 25. The lug 23 is preferably split vertically adjacent each end as at 26 and 27 and its middle portion 23^a, through which the shaft 22 passes, is preferably bored out to a diameter slightly larger than that of the shaft. The end portions 23^b and 23^c are bored to substantially the diameter of the shaft and are split and provided with clamping bolts 28 so that the shaft 22 may be securely clamped thereby. The generator 10 is therefore rigidly connected and suspended from the rotatably supported shaft 22.

The axis of the shaft 22 is preferably substantially parallel with the axis of the gen-

erator 10. The plate 19 which, as above described, supports the shaft 22 is preferably secured upon its supporting straps 16 and 17 by means of bolts shown as four in number, 29, 30, 31 and 32 respectively. These bolts pass through round openings in the members 16 and 17 and all but one thereof, as 29, are provided with the slotted openings through the plate 19 as shown in Figure 1. The plate 19 may thus be swung about the bolt 29 as an axis for transverse adjustment of the shaft 22, and hence of the axis of the generator. In this manner, after mounting of the parts, the axis of the generator may be conveniently adjusted into parallelism with the car axle from which it is to be driven. Preferably the plate 19 is provided with a pair of lugs 33 and 34 respectively overhanging the sides of the supporting members 16 and 17. Through these lugs are threaded bolts 35 and 36 by means of which the position of the plate 19 about the bolt 29 may be adjusted. After adjustment the plate 19 and the members 16 and 17 are securely clamped together by tightening up on the bolts 29, 30, 31 and 32.

Secured to the casing of the generator 10 is an arm 37 extending outwardly, forwardly of and above the pulley 11. This arm 37 is provided at its end with a pair of upstanding flanges 38 through which passes a pin 39. The pin 39 passes through a member 40, which at its opposite end is slotted as shown at 41 in Figure 2. Through this slot 41 extends a pin 42 which passes through the ears 43 of a bracket 44. The bracket 44 is secured, as by rivets 45, to a member 46 secured between the two center sill members 13 and 14. About the member 40 is a spiral tension spring 47, the ends of which are hooked over the pins 39 and 42. As viewed in Figure 2 therefore the spring 47 tends to swing the generator 10 in a counter-clockwise direction about its pivot, while the belt acting upon the pulley 11, tends to swing the generator in a clockwise direction about its pivot. The tension in the driving belt therefore is governed by the spring 47 and is thereby maintained always constant. The generator swings about its axis of suspension in response to variations in the length of the driving belt or to movements of the car axle affecting the distance between the latter and the pulley 11, but in normal operation this swinging of the generator is very slight. However, it is important that the bearings of the suspension shaft 22 be kept properly lubricated to avoid danger of the bearings sticking and the consequent loss of the driving belt.

In Figure 4 one end of the suspension shaft 22 and its bearing are shown in enlarged detail. The bearing 21 supported in the part 19^a of the plate 19 is clamped in place thereon by a removable cap 48 se-

cured by bolts 49 shown in Figure 2. The bearing is held from axial movement by means of its end flanges 21^a. Over the end of the supporting shaft 22 is removably secured a hollow cap 50 by means of bolts 51 threaded into the flange 21^a of the bearing 21. The inside of this cap 50 forms a reservoir for lubricant which is forced thereinto from a grease cup 52. The inner surface of the bearing 21 is provided with a plurality of helical grooves 53 for the passage of grease or other lubricant from the reservoir within the cap 50. Packing washers 54 and 55 are preferably provided at each end of the bearing 21. It will be seen that the grease forced from the grease cup 52 into the reservoir 50 has access thereto through the grooves 53 so that it lubricates the entire surface of the bearing without the necessity of any movement of the shaft 22 or at least necessitating only a slight rotative movement of the shaft. The bearing is thus dependably lubricated at all times and danger of its sticking is substantially avoided. The lubricant may move through the grooves 53 to all parts of the bearing surface, not being subject to the pressure of the shaft while in these grooves.

The mounting described above provides for the suspension of the generator and its associated parts without the necessity of cutting away any portion of the sills of the car and thus weakening the same. The supporting members 16 and 17 being of forged steel may be shaped as required to suit the type of car upon which the generator is to be mounted. The center line of the car, it will be understood, is substantially midway between the two members 13 and 14 of the center sill and it will be seen that with this apparatus the pulley of the generator may be conveniently positioned substantially on the center line of the car. This is of importance in that the effect upon the generator of the turning of the car axle on curves is minimized. It will be further seen that this mounting is readily adaptable to cars wherein the center sill comprises only one beam instead of two. Furthermore by means of this mounting the generator pulley may be positioned substantially beneath the retracting spring whereby torsional strain upon the generator supporting lug and the supporting shaft is practically avoided.

In operation, in case it becomes necessary to remove the bearing shaft 22, the generator is jacked up, the bolts 28 in the lug 23 are loosened, the cap 50 is removed and the shaft may be drawn out axially by means of a bolt inserted in the threaded recess 56 provided in the end of the shaft. To remove the bearings 21, it is necessary to simply remove the caps 48 and jack the generator up a little higher. In case the bear-

ings should become badly stuck to the shaft, it may be easily removed therefrom by cutting.

From the above it will be seen that there is herein provided an apparatus which embodies the features of this invention and attains the objects thereof and that the same is well adapted to meet the requirements of practical use.

10 As many possible embodiments may be made of the above invention and as many changes might be made in the embodiment above set forth, it is to be understood that all matter hereinbefore set forth is to be interpreted as illustrative and not in a limiting sense.

I claim as my invention:

1. In a generator suspension for railway cars, in combination, supporting means secured beneath the car, a shaft journaled adjacent its two ends in said supporting means, a generator, and means clamped about said shaft between said two journals suspending said generator therefrom.

25 2. In a generator suspension for railway cars, in combination, supporting means mounted beneath the car, a shaft journaled in said supporting means, a generator, and a supporting lug connected to said generator and through which said shaft passes, said lug having a loose fit on said shaft at its central portion and being clamped securely about the same adjacent its ends.

3. In a generator suspension for railway cars, in combination, supporting means mounted beneath the car, bearings carried upon said supporting means, a shaft rotatably supported in said bearings, a generator, and means connected to said generator and clamped to said shaft to support said generator from said shaft, said bearings and said last means being capable of being released from said shaft to permit removal of said shaft without removal of said generator.

4. In a generator suspension for railway cars, in combination, supporting means mounted beneath the car, bearings carried upon said supporting means, a shaft rotatably supported in said bearings, a generator, and means connected to said generator and clamped about said shaft to support said generator from said shaft, said last means being capable of being released from said shaft to permit removal of said shaft in an axial direction therefrom and from said bearings.

5. In a generator suspension for railway cars, in combination, supporting means mounted beneath the car, bearings carried upon said supporting means, a shaft rotatably supported in said bearings, a generator, and means connected to said generator and clamped about said shaft to support said generator from said shaft, said

last means being capable of being released from said shaft to permit removal of said shaft in an axial direction therefrom and from said bearings, and said bearings being removable from said supporting means.

6. In a generator suspension for railway cars, in combination, supporting means mounted beneath the car, spaced bearings carried by said supporting means, a shaft rotatably supported in said bearings, a generator, and means removably clamped about said shaft intermediate of said spaced bearings and supporting said generator from said shaft, said bearings having means for distributing lubricant thereover.

7. In a generator suspension for railway cars, in combination, supporting means beneath the car, a shaft journaled adjacent its two ends in said supporting means, a generator, means removably clamped about said shaft intermediate of said two journals supporting said generator from said shaft, and removable means secured to said supporting means adjacent each end of said shaft adapted to form reservoirs for lubricant to said journals and normally preventing removal of said shaft in an axial direction.

8. In a generator suspension for railway cars, in combination, a supporting shaft, bearings mounted beneath the car and rotatably supporting said shaft adjacent its ends, a generator, means clamped about said shaft intermediate said bearings and carrying said generator, and means adjacent an end of said shaft adapted to permit removal thereof in an axial direction from said bearing and said clamping means.

9. In a generator suspension for railway cars, in combination, supporting means beneath the car secured to a center sill member thereof and projecting laterally therefrom, a generator pivotally suspended from said supporting means about a transverse axis to swing toward and away from an axle of the car, said generator having upon its armature shaft a pulley adapted to be driven by belt from said axle, an arm secured to said generator and extending therefrom laterally beneath said center sill member, and a spring mounted at the side of said sill member opposite from said supporting means connected to said arm and adapted to urge said generator to swing about its pivot in opposition to the pull of said belt thereon, said pulley being positioned beneath said spring and substantially in vertical alinement therewith.

10. In a generator suspension for railway cars, in combination, supporting means secured beneath the car and extending from a center sill member toward a side sill member, a shaft journaled in said supporting means having its axis transversely of the car, a generator removably fixed to said shaft and suspended therebeneath so that

- its armature shaft projects beneath said center sill member, said armature shaft having thereon a pulley adapted to be driven by belt from an axle of the car, an arm secured to said generator and projecting laterally therefrom between said center sill member and said pulley, and a spring secured to said center sill member connected to said arm to urge said generator to swing about the axis of said shaft in opposition to the pull of said belt.
11. In a generator suspension for railway cars, in combination, a supporting shaft, bearings mounted beneath the car and rotatably supporting said shaft adjacent its ends, a generator, means clamped about said shaft intermediate of said bearings and carrying said generator, an end of said shaft having means adapted to be engaged by an instrument for removal of said shaft in an axial direction from said bearings and said clamping means.
12. In a generator suspension for railway cars, in combination, supporting means beneath the car, a shaft journaled adjacent its two ends in said supporting means, a generator, means removably clamped about said shaft intermediate said two journals suspending said generator from said shaft, and means covering the end of said shaft adjacent one of said journals adapted to form a reservoir for lubricant and removable to permit removal of said shaft in an axial direction.
13. In a generator suspension for railway cars, in combination, supporting means secured beneath the car and extending between one of the center sill members thereof and a side sill member, a generator pivotally suspended from said supporting means having upon its armature shaft a pulley adapted to be driven by belt from the car axle, a member secured to said generator and extending toward the center line of the car beneath the adjacent center sill member and free from interference therewith, and a spring mounted between the two center sill members and connected to said last member adapted to urge said generator to swing about its pivot in opposition to the pull of said belt thereon.
14. In a generator suspension for railway cars, in combination, a pair of spaced horizontal supporting members extending outwardly from the center sill of the car, means bridging the space between said supporting members providing a pair of spaced bearing supports, bearings removably positioned in said bearing supports, a shaft supported adjacent its ends in said bearings, and a generator suspended from said shaft between said bearings.
15. In a generator suspension for railway cars, in combination, a pair of spaced horizontal supporting members extending outwardly from the center sill of the car, means bridging the space between said supporting members providing a pair of spaced bearing supports, bearings removably positioned in said bearing supports, a shaft supported adjacent its ends in said bearings, and a generator having means extending upwardly between said two bearings and clamping said shaft, said generator being thereby suspended.
16. In a generator suspension for railway cars, in combination, a pair of spaced horizontal supporting members extending outwardly from the center sill of the car, a plate member supporting upon said supporting members having an opening between said two members and bearings at either side of said opening, a shaft extending across said opening and supported adjacent its ends in said bearings, and a generator beneath said supporting plate having means extending upwardly through said opening and clamping said shaft, said generator being thereby suspended.
- In testimony whereof, I have signed my name to this specification this 19th day of February, 1924.

GEORGE E. HULSE.
